UNITED STATES PATENT OFFICE.

WILLIAM EVERETT VER PLANCK, OF NEW YORK, AND CHARLES EDUARD LUCKE, OF KINGSBRIDGE, NEW YORK.

VAPORIZER.

SPECIFICATION forming part of Letters Patent No. 767,456, dated August 16, 1904.

Application filed February 24, 1902. Serial No. 95,267. (No model.)

To all whom it may concern:

Be it known that we, WILLIAM EVERETT VER PLANCK, a resident of the borough of Manhattan, and CHARLES EDUARD LUCKE, a resident 5 of Kingsbridge, borough of the Bronx, in the city, county, and State of New York, citizens of the United States, have invented a new and Improved Vaporizer, of which the following is a full, clear, and exact description.

10 This invention relates to a vaporizer for hydrocarbon oils. It is useful for various purposes, but is especially intended for supplying fuel to internal-combustion engines.

The object is to provide means for maintaining a supply of hydrocarbon or other vapor under constant pressure, the vapor to be mixed with air and supplied to the engine in the usual or any desired manner and affording an unfailing supply of vapor fuel for the 15 engine notwithstanding irregularities in the operation of the same. This end we attain by providing a receiver in which a definite volume of the oil may be constantly maintained and heated, preferably, to or above the boiling-point. The receiver is fitted with means 20 for maintaining the oil at a practically constant level and the vapor at approximately a predetermined pressure. The upper part of the receiver is in connection with the engine 25 to supply vapor thereto.

This specification is an exact description of one example of our invention, while the claims define the actual scope thereof.

Reference is to be had to the accompanying 35 drawing, forming a part of this specification, in which the figure represents a sectional elevation of the invention.

a indicates the receiver, which according to the construction here shown is provided with 40 fire-tubes *b*. This receiver may be most economically heated by causing the exhaust-gases of the engine to pass through the fire-tubes in the manner indicated by the arrows in the drawing.

45 *c* indicates a means for drawing off vapors from the upper part of the receiver, and *d* indicates the supply-pipe for the liquid fuel. This supply-pipe is preferably in connection

with an elevated tank *d*³ for a purpose which will hereinafter appear. 50

d' indicates a branch of the pipe *d*, which passes into the receiver *a* at or immediately adjacent to the bottom thereof.

e indicates a cock for controlling this branch, and *f* indicates a check-valve opening into the 55 receiver, as the arrow shows.

*d*² indicates a second branch of the pipe *d*, this branch leading into the receiver at a point above the branch *d'*, and *g* indicates a check-valve in the pipe *d*², the check-valve *g* opening into the pipe *d*, as the arrow shows. 60

The operation of this apparatus is as follows: Oil is introduced into the receiver until it reaches the desired level. This level is at or near the pipe *d*² for reasons which will be 65 hereinafter set forth. If the receiver is not under sufficient heat at the starting operation, the cock *e* may be closed until the proper degree of vaporization takes place within the receiver, after which the cock should be 70 opened and kept open at all times during the operation of the vaporizer. The heat from the exhaust of the engine or from any other source desired causes the liquid fuel to boil in the receiver, and the vapor given off accumulates above the oil. When the pressure 75 of vapor in the receiver becomes sufficiently great to overcome the pressure of the oil in the pipe *d*, the vapor will pass out through the pipe *d*², past the loaded check-valve *g*, and 80 into the pipe *d*, where the vapor will be condensed by the comparatively cold oil therein.

If the oil rises in the receiver above the branch pipe *d*², the pressure of vapor will force the surplus of oil out through the pipe *d*². The 85 pipe *d'* supplies the oil to the receiver when needed. The vapor is taken to the engine by way of the pipe *c*, as will be understood.

In connection with this apparatus it will be observed that a constant body of oil is always 90 maintained in the receiver. The amount of the oil is automatically controlled by the devices explained, also a constant pressure of vapor above atmospheric pressure is maintained. In practical operation the apparatus 95 is blowing at all times—that is to say, the

vapor is at sufficient pressure to pass into the pipe *d* against the pressure therein. This keeps the vapor at a certain pressure, and this pressure may be easily regulated by regulating the pressure of the oil in the pipe *d*. This is preferably done by the elevated tank referred to hereinbefore, and by placing the tank at one elevation or another the pressure in the pipe may be varied. Other means, however, may be used for this purpose, as will be readily understood. This apparatus provides, therefore, a supply of vapor under a constant pressure above atmospheric pressure which is always at the command of the engine and is sufficient to meet any emergencies that might arise.

An important feature of the apparatus is the maintenance of a body of liquid fuel in the receiver. This avoids carbonization and insures the effective operation of the apparatus, the essential point in which is the generation of the vapor within the receiver from the body of oil maintained therein. This vapor being maintained under pressure in the receiver is continuously subjected to the heat thereof, thus keeping it in the form most productive of effective results in the engine-cylinder.

The apparatus here shown and described is considered by us to be the most effective embodiment of the invention; but we desire it understood that it is not our purpose to limit ourselves to this form of the apparatus, but consider ourselves entitled to all forms thereof which embody the principle of action pointed out above and defined in the claims.

Having thus described our invention, we claim as new and desire to secure by Letters Patent—

1. A vaporizer for hydrocarbon oils, comprising a receiver adapted to be heated, a supply-pipe for the liquid oil, said pipe having two branches leading into the receiver at different elevations, and check - valves in the branches, the check-valve of the lower branch opening into the receiver and the check-valve of the upper branch opening into the supply-pipe.

2. A vaporizer, comprising a receiver adapted to be heated and having an outlet for the vapor, a liquid-fuel supply, and means for exhausting the excess vapor into the liquid-supply, whereby to condense said excess vapor, said means comprising a passage leading from the receiver at a point above the fuel-inlet and serving also to carry off the excess fuel under the pressure of the vapor.

3. A vaporizer, comprising a receiver adapted to be heated and having an outlet for the vapor, a liquid-fuel supply, and means for exhausting the excess vapor into the liquid-supply, whereby to condense said excess vapor, said means comprising a tube leading from the receiver at a point above the fuel-inlet and a check-valve in the tube and opening toward

the fuel-supply, whereby also to carry off the excess fuel under the pressure of the vapor.

4. In a vaporizer for hydrocarbon fuel, the combination of a source of liquid-supply, a closed receptacle, means for heating it, a regulator for maintaining a predetermined level of the liquid within the receptacle to prevent carbonization, and a means for condensing the vapor produced in excess of that required to maintain a predetermined pressure.

5. A vaporizer for hydrocarbon oils, comprising a receiver adapted to be heated and having an outlet for drawing off the vapor generated, and means for supplying the liquid oil to the receiver, said means maintaining constantly a certain body of liquid oil in the receiver, whereby to prevent carbonization and to permit instantly replenishing the vapor-supply in the receiver from the body of superheated liquid oil maintained therein, and said means including devices for exhausting the excess vapor from the receiver against a certain set pressure, whereby to maintain the vapor in the receiver at a predetermined pressure.

6. A vaporizer for hydrocarbon oils, comprising a receiver adapted to be heated and having an outlet for drawing off the vapor generated, and means for supplying the liquid oil to the receiver, said means maintaining constantly a certain body of liquid oil in the receiver, whereby to prevent carbonization and to permit instantly replenishing the vapor-supply in the receiver from the body of superheated liquid oil maintained therein, and said means including devices for exhausting the excess vapor from the receiver into the liquid-oil supply at a point below the level thereof, whereby a certain pressure is opposed to the vapor-exhaust and the vapor in the receiver is thereby maintained at a predetermined pressure, and whereby also the exhaust-vapor is condensed in and by the liquid-oil supply.

7. A vaporizer for hydrocarbon oils, comprising a receiver adapted to be heated, a liquid-oil-supply pipe leading into the receiver, a check-valve in the said supply-pipe, the check - valve opening into the receiver, a branch pipe leading from the receiver, at a point above the point of entry of the supply-pipe, to and into said supply-pipe, and a check-valve in the branch pipe and opening into the supply-pipe, for the purpose specified.

8. A vaporizer for hydrocarbon oils, comprising a receiver adapted to be heated, a liquid-oil-supply pipe leading into the receiver, a check-valve in said supply-pipe, the check-valve opening into the receiver, and a branch pipe leading from the receiver, at a point above the point of entry of the supply-pipe, to and into said supply-pipe, for the purpose specified.

9. In a vaporizer for hydrocarbon fuel, the combination of a source of liquid-supply, a

receptacle, means for heating the receptacle, a regulating mechanism for maintaining a predetermined amount of liquid within the receptacle to prevent carbonization, and a means 5 for discharging the excess vapor back into the original source of liquid-supply where it is condensed when the pressure within the receptacle exceeds a predetermined amount.

10. In a vaporizer for hydrocarbon fuel, the combination of a receptacle in which the liquid is vaporized, and maintained under pressure, a means for heating the receptacle, a device for permanently retaining a certain amount of liquid in the receptacle against the internal 15 pressure to prevent carbonization, a valve

which automatically opens under conditions of excess pressure and discharges such an amount of vapor into a closed space as will relieve said excess and permit the vapor to condense, and a source of supply which automatically feeds liquid to the receptacle as it is consumed. 20

In testimony whereof we have signed our names to this specification in the presence of two subscribing witnesses.
